UNITED STATES PATENT OFFICE.

CHARLES SMITH, OF PITTSBURGH, PENNSYLVANIA.

ELECTRICAL CONNECTER FOR TRANSMISSION LINES.

Application filed June 21, 1924. Serial No. 721,489.

My invention relates to electrical conductors and more particularly to connectors suitable for temporary use and assistance in repairing broken transmission lines, as well as to a method for connecting such lines.

One object of my invention is to provide means whereby a broken transmission line, particularly one carrying high voltage, may be repaired with safety and without substantial interruption to the service.

Heretofore, when transmission lines have become broken it has been deemed necessary to shut off the current until a repair has been fully completed, owing to the danger of electrocution and to the liability of injury to the repairman through arcing when the broken ends of a transmission line from which the current has not been shut off are brought together. The difficulty in making repairs is further increased where there are a plurality of conductors located adjacent to one another as in phase system of distribution, and especially where there are wires on cross arms above or below the broken wire.

By my invention I provide a device whereby the broken ends of a line may be temporarily supported and a current shunted around such ends while they are being rejoined.

One manner in which my invention may be practiced is shown in the accompanying drawing wherein Fig. 1 is a view, in front elevation, of one side of the connector which I employ; Fig. 2 is a view of the opposite side thereof; Fig. 3 is a plan view thereof, and Fig. 4 is a cross sectional view of the device of Fig. 1.

For convenience of explanation, I have shown my device as applied to broken wire 5 of a 3-wire distribution system, the numbers 5^a and 5^b representing the broken ends of the line 5.

The connector consists of a block 6 of insulating material to which a switch blade 7 is pivoted by a bolt 8 that extends through the block of base 6. The opposite end of the blade 7 cooperates with switch jaws 9 that are secured to the block 6 by a bolt 9^a. At the opposite side of the block 6 is shown clamping plates 10 and 11 for holding the broken wire 5^b. Nuts 12 are employed for drawing the plate 11 tightly against the wire 5^b, by reason of their threaded engagement

with the bolts 9^a and 13 that are pointed at their outer ends to facilitate the placing of the nuts 12 thereon. The plates 10 and 11 and the bolt 9^a serve to electrically connect the switch jaws 9 with the wire 5^b.

In order to more firmly connect the block 6 to the wire 5^b, I provide a second pair of clamping plates 14 that are drawn together by nuts 15 that engage bolts 16 in a manner similar to the arrangement with respect to bolts 9^a and 11.

An operating cord or rope 17 is connected to the outer end of the switch blade 7 and passes over a sheave 18 that is secured to the block 6 by means of a bolt or pivot pin 19 and a yoke member 20.

The bolt 8 together with a nut 8^a may serve as a terminal for a conductor 21. The other end of this conductor is secured to a clamping plate 22 with which cooperates another plate 23 the plates being drawn together by nuts 24 and bolts 25. The plates 22 and 23 serve to clamp the wire end 5^a.

A pigtail connector 26 is also provided, one end of such connector being secured to the switch blade 7 and the other end thereof secured at 28 to the conductor 21.

When it is desired to repair a broken line, one end thereof is connected to the block 6 as above explained, and the other end thereof connected to the conductor 21, through the clamping plates 22 and 23. The switch blade 7 during the making of these connections is preferably in open position as indicated in dotted lines in Fig. 1. Thereafter the switch is closed, through the medium of the rope 17, and current will flow through the switch jaws 9, the switch blade 7, the shunt connection 26, and conductor 21. A latch 30 may be provided to insure against accidental opening of the switch. The operator may then with a reasonable degree of safety repair the broken ends 5^a and 5^b, as the current will be flowing through the connections just described.

It will be seen that my invention is particularly advantageous on transmission lines that are located at considerable height above the ground and adjacent to other live wires, for the reason that the repairman may connect the broken ends to the switch while said ends are dead and may then operate the rope to close the switch.

If an attempt were made to connect the

broken ends with current on the line, the resulting arcs would perhaps flash into the repairman's eyes, causing him to lose the sight of his eyes, or startle him into touching an adjacent live wire.

The shunt 26 is provided as an additional precaution to avoid slight arcing that would occur if the pivot connection of the switch blade became slightly loose.

- 10 By connecting the wire ends 5^a and 5^b to opposite sides of the block, as will appear more clearly in Fig. 3, a greater measure of safety is present in that there is less liability for such ends to accidentally touch during the connection of switch block thereto. Further, a better balance of the switch block is obtained in that it will tend to lie in a vertical plane when suspended from the wires, thus facilitating movement of the switch plate and rendering the device more stable.
- 15
- 20

Various changes in detail and general arrangement may be made without departing from the spirit and scope of the invention as defined in the accompanying claims:

What I claim is:

- 25 1. An electrical wire fastening device comprising a switch block, and means on said block for detachably connecting a conductor thereto, a flexible electrical connection secured to said block, means on said connection for detachably engaging a second conductor, and a movable contact device for controlling the circuit through said first-named conductor and said flexible connector.
- 30 2. An electrical wire fastening device comprising a switch block, a conductor clamp secured to one side of said block and having a portion thereof extending through said block, a stationary contact member secured to said portion, a movable contact member, pivotally mounted on said block for engagement with said contact member, a flexible connector secured to said movable contact
- 35
- 40

member, and means for securing said flexible connector to a second conductor.

3. An electrical wire fastening device comprising a conductor clamp secured to one side of said block and having a portion thereof extending through said block, a stationary contact member secured to said portion, a movable contact member, pivotally mounted on said block for engagement with said stationary contact member, a flexible connector secured to said movable contact member, means for securing said flexible connector to a second conductor, a pull cord attached to said movable contact member, and a guiding sheave on said block for said pull cord.

4. A device for use in connecting the ends of electrical conductors, comprising a switch, means for temporarily securing the switch to one conductor at a point removed from the end thereof, means for effecting a temporary shunt connection from said switch to a point removed from the end of another conductor, whereby the conductor ends may be supported in convenient position for permanent connection to one another, and means for operating said switch to make and break a circuit through said shunt.

5. A device for use in permanently connecting the ends of electrical conductors, comprising a switch, means for detachably connecting one pole of the switch to a conductor at a point removed from the end thereof, and means for connecting another pole of the switch to a conductor at a point removed from the end thereof, the connecting means being so arranged that the extremities of the conductors may be supported in position for joining to one another.

In testimony whereof I, the said CHARLES SMITH, have hereunto set my hand.

CHARLES SMITH.
